DOOR LATCH

John C. Ehrke, Le Center, Minn.

Application July 10, 1946, Serial No. 682,517

5 Claims. (Cl. 292—123)

1

My invention relates to improvements in door latches and operating mechanism therefore, intended for general use but especially well adapted for use in connection with screen doors.

The object of this invention is to provide a highly efficient door latch and operating mechanism that is easy to install and operate.

To the above end the invention consists of the novel devices and combination of devices herein-after described and defined in the claims.

In the accompanying drawings, which illustrate the invention, like characters indicate like parts throughout the several views.

Referring to the drawings—

Fig. 1 is a fragmentary front elevation of an outside door frame to which is hinged a screen door having the invention applied thereto;

Fig. 2 is a view partly in elevation and partly in section taken on the line 2—2 of Fig. 1 on an enlarged scale;

Fig. 3 is a fragmentary view partly in elevation and partly in section taken on the line 3—3 of Fig. 2;

Fig. 4 is a fragmentary detail view partly in elevation and partly in section taken on the line 4—4 of Fig. 5;

Fig. 5 is a fragmentary detail view partly in elevation and partly in section taken on the irregular line 5—5 of Fig. 4;

Fig. 6 is a fragmentary detail view partly in elevation and partly in section taken on the line 6—6 of Fig. 4; and

Fig. 7 is a detail view with some parts sectioned on the line 7—7 of Fig. 4.

The numeral 8 indicates an outside door frame to which a screen door 9 is hinged at 10 to swing outwardly.

The invention includes a latch assembly 11, comprising a cylinder 12, a pivot pin 13, a bearing sleeve 14, a latch bar 15, a lever 16, a handle 17, and a double sear spring 18. The cylinder 12, which carries the entire latch assembly 11, is mounted in a transverse hole in the outer stile of the screen door 9.

The pivot pin 13, on which the bearing sleeve 14 is mounted, extends diametrically through the cylinder 12 and is secured thereto at its ends. The latch bar 15 extends longitudinally through the cylinder 12 and is intermediately pivoted on the bearing sleeve 14. On the inner end of the latch bar 15 is a detent 19 having a cam acting edge 20.

The lever 16 is bifurcated, straddles the inner end portion of the latch bar 15 and is pivoted on the bearing sleeve 14. As indicated at 21, the latch bar 15 and lever 16 have beveled contact, whereby when the lever 16 is moved rearwardly,

the latch bar 15 is carried with it to release its detent from a latch plate as will presently appear. On the other hand, the latch bar 15 is free to be moved relative to the lever 16 to release its detent 19 from the latch plate. The lever 16 at its free end portion is bifurcated and a roller 22 is journaled to and between the prongs 23 thereof.

As shown, the handle 17 is in the form of a round bar having at one of its end portions, a radially projecting longitudinally split sleeve 24. This sleeve 24 is telescoped onto the outer end portion of the latch bar 15 and adjustably secured thereto for doors of different thicknesses by a nut equipped bolt 25 insertable through aligned holes 26 in said sleeve and latch bar. The sear spring 18 is formed of a single piece of spring wire folded upon itself and the ends thereof are connected by a sleeve 27. The longitudinal members of the spring 18 are coiled at 28 and encircle the bearing sleeve 14 with the lever 16 therebetween. The connecting sleeve 27 on the spring 18 engages the cylinder 12, as a base of resistance and said spring at its other end is seated in notches 29 in the back of the latch bar 15 and the lever 16. This spring 18 normally holds the latch bar 15 and the lever 16 in operative positions in which they are pressed against the cylinder as a stop.

When the door 9 is closed the detent 19 engages a latch plate 30 on the door frame 8 and holds said door closed. In closing the door 9 the cam 20 on the detent 19 engages the latch plate 30, retracts the latch bar 15 and permits the detent 19 to pass said latch plate and thereafter be projected by the spring 18 back of the latch plate 30 and thereby hold the door 9 closed.

To release the detent 19 from the outside of the door 9, an outward pull on the handle 17 will rock the latch bar 15 on the bearing sleeve 14 and thereby retract the detent 19 and release the latch so that the door may be opened.

An escutcheon 31, secured on the outer face of the door 9 by screws 32, covers the outer end of the cylinder 12 and has a slot 33 in which the respective end portion of the latch bar 15 works. On the inner face of the door 9 is an escutcheon 34, secured thereto by screws 35, covers the respective end of the cylinder 12 and has a slot 36 in which the respective end portion of the latch bar 15 works.

A hand bar 37, which extends substantially the full width of the door 9, on the inside thereof, is provided for operating the lever 16, and hence the latch bar 15, from the inside of said door. This hand bar 37 is a round tube pivotally attached

at one of its ends to a post 38 for swinging movement perpendicular to the plane of the door 9. The post 38 has a base flange 39 that rests on the inner stile of the door 9 and is secured thereto by screws 40. The post 38 at its outer end portion is bifurcated and extends into the hand bar 37 through an aperture 41 therein. A pivot pin 42 extends through aligned holes in the hand bar 37 and the post 38 to pivotally connect said hand bar to the post 38.

A sear spring 43 is provided for swinging the hand bar 37 away from the door 9. This spring 43 has a coil 44 that encircles the pivot pin 42. One arm of the spring 43 extends into the post 38 and engages the same as a base of resistance. The other arm of the spring 43 extends longitudinally into the hand bar 37, engages the outer side thereof and is under strain to swing said bar outwardly on the pivot pin 42.

The roller 22 and the respective end portion of the latch bar 15 extend into the hand bar 37 through an aperture 45 therein. The roller 22 is of such size as to run on diametrically opposite surfaces of the hand bar 37. A plug 46 normally closes the outer end of the hand bar 37 and is held in place by a nut equipped bolt 47 that extends through aligned holes in the hand bar 37 and the plug 46. The inner end of the hand bar 37 is permanently closed as indicated at 48.

Referring again to the latch plate 30, the same is secured to the door frame 8 by a pair of screws 49, one of which extends through a slot 50 in said plate and the other thereof extends through a hole 51 in said plate. In attaching the latch plate 30 to the door frame 8 one of the screws 49 is inserted through the slot 50 and turned into said frame. Next, the latchplate 30 is endwise adjusted into proper relation to the detent 19 and then the other screw 49 is inserted through the hole 51 and turned into the door frame 8. This last screw 49 positively holds the latch plate 30 when adjusted.

To hold the latch bar 15 and the lever 16 with the detent interlocked with the latch plate 30 and thereby lock the door 9 closed, I provide a catch 52 in the form of an arm pivoted to a fixed stud 53 on the escutcheon 34. A coiled spring 54, encircling the stud 53 is compressed between the catch 52 and a washer and nut 55 on said stud and yieldingly holds said catch when positioned. On the outer end portion of the catch 52 is a knob 56 by which said catch may be moved. The catch 52 has an edge portion 57 eccentric to the pivot of the catch 52. This eccentric edge 57, when the catch 52 is positioned as shown in Fig. 6, engages the latch bar 15 and the lever 16 and holds the same with the detent 19 interlocked with the latch plate 30. A stop shoulder 58 on the catch 52 limits the movement of said catch into an operative position.

To open the door 9, from the outside, it is only necessary to pull outwardly on the handle 17 to move the latch bar 15, pivotally, relative to the lever 16 and withdraw the detent 19 from engagement with the latch plate 30. When operating the latch to open or close the door 9, the catch 52 must of course be released.

To open the door 9, from the inside, it is only necessary to press the hand bar 37 toward said door and move the same pivotally. This movement of the hand bar 37 will cause the roller 22 to travel on said bar and thereby move the lever 16 pivotally. Pivotal movement of the lever 16

will carry with it the latch bar 15 and thereby release the detent from the latch bar 15.

Obviously the hand bar 37 may be operated by hand by pressing the body thereagainst or by pressing the same with a bundle carried in the arms.

To apply the latch to a door, that opens in the opposite direction from that shown in the drawings, it is only necessary to remove the catch 52 from the stud 53, remove the knob 56 from said catch, which is releasably held by a screw 59. Then turn the catch 52 other side up, replace the knob 56 on the catch 52 and said catch on the stud 53. With this slight adjustment the latch is ready to be attached to a door.

From what has been said, it will be understood that the invention described is capable of modification as to details of construction and arrangement within the scope of the invention herein disclosed and claimed.

What I claim is:

1. In a latch of the class described, a hinge member applicable to the inner side of a door, a hand bar pivoted at one of its end portions to the hinge member for movement toward or from the door, a cylinder adapted to be mounted in a transverse bore in the door, a lever and a latch bar extending into the cylinder from opposite sides of the door, said lever being pivoted at its inner end portion to the cylinder, said latch bar being intermediately pivoted to turn independently of the lever about the axis of its pivot, said lever, at its outer end portion, being slidably connected to the hand bar to be operated thereby, a handle on the outer end of the latch bar, and a detent on the inner end portion thereof, a spring yieldingly holding the latch bar with its detent projected, said lever, when operated by movement of the hand bar toward the door, engaging the latch bar and moving the same therewith to retract the detent.

2. The structure defined in claim 1, further including a second spring under strain to move the hand bar away from the door.

3. The structure defined in claim 1 in which the pivoted end portion of the lever is bifurcated with the inner end portion of the latch bar extending between the prongs thereof, the inner end portion of the latch bar overlapping the lever at the crotch thereof for moving said latch bar therewith when said lever is operated by a movement of the hand bar toward the door to retract the detent.

4. The structure defined in claim 1 in which the hand bar is tubular and the lever has internal sliding contact therewith.

5. The structure defined in claim 1 in which the hand bar is tubular and the lever has on its outer end portion a roller that extends into the outer end portion of the hand bar and has rolling contact therewith.

JOHN C. EHRKE.
